UNITED STATES PATENT OFFICE

JESSE G. KING, OF DAYTON, OHIO, ASSIGNOR TO FRIGIDAIRE CORPORATION OF DAYTON,
OHIO, A CORPORATION OF DELAWARE

REFRIGERATING APPARATUS

Application filed January 30, 1928. Serial No. 250,407.

This invention relates to refrigerating apparatus and more particularly to an improved refrigerating system and improved cooling elements therefor.

5 It is one of the objects of this invention to provide an improved form of cooling element which is economical to manufacture and which has high cooling capacity within a small volume.

10 It is another object of this invention to provide an improved cooling element for chilling circulating water which minimizes the danger of the water becoming mixed with the refrigerant in the event of accident or 15 of failure of some part of the apparatus.

Further objects and advantages of the present invention will be apparent from the following description, reference being had 20 to the accompanying drawings, wherein a preferred form of embodiment of the present invention is clearly shown.

In the drawings:

Fig. 1 is a diagrammatic representation of 25 a refrigerating system constructed in accordance with the present invention.

Figs. 2 and 3 are a longitudinal section and an end elevation respectively, of one form of my improved cooling element.

30 Figs. 4 and 5 are a longitudinal section and an end elevation, respectively, of another form of cooling element.

Figs. 6 and 7 are a longitudinal section and an elevation respectively, of still another form of cooling unit.

35 Figs. 8 and 9 are a longitudinal section and an end elevation, respectively, of a fourth form of cooling element.

In refrigerating systems employing sulfur dioxide for refrigerant it is very common to have water in heat exchange relation with the refrigerant, for example, frost collected on a cooling element, water for cooling a condenser, or circulating water to be cooled by a cooling element. In each of these circumstances there is likelihood of water getting in to the refrigerating system due to 40 leaks, imperfect joints, or accident such as freezing of the water. This is particularly true of where there are joints in the heat conducting path between the water and the re- 45 frigerant. It is well known that water when mixed with sulfur dioxide forms sulfuric acid which is highly destructive to the apparatus. Consequently care must be taken to prevent water from getting into the system. 55 One of the objects of my invention is to provide a refrigerating system in which there are no joints in the heat conducting path between the water and refrigerant so that the water can get in the refrigerant only thru rupture of the entire cooling element. 60

It is a further object of the invention to provide a cooling element for chilling circulating water, in which, in the event of 65 freezing of the water, any rupture will occur in such a manner as to prevent water from getting into the refrigerant.

Referring to Fig. 1, my system comprises a conventional compressor 20 actuated by a 70 motor 21 for circulating refrigerant thru one or more refrigerating elements 22 and 23. The compressor draws gaseous refrigerant from the refrigerating elements 22 and 23 by suction or vapor conduits 24 and 25 respectively, 75 compresses the refrigerant and delivers it to a condenser 26 where it is liquefied and from which it flows to the high pressure or liquid conduit 28, if desired thru a receiver or reservoir 29, in which it may be stored 80 against demand for refrigeration by the refrigerating elements. The condenser is cooled by water supplied to it by a conduit 26a. The compressor may be started and stopped by means of a switch 30 which controls the motor 21, and which may be opened and closed in response to the refrigerating 85 demand of either or both of the refrigerating elements 22 and 23. Each of the cooling elements in the system, including the condenser and both evaporators, that is, all parts of the system where water and refrigerant are thermally associated, are constructed in accordance with my invention as shown in Figs. 2 to 9 inclusive. Figs. 2 and 3 show one form 90 of cooling element which includes both a condenser for the gaseous refrigerant delivered under pressure from the compressor, and a reservoir for storing the liquefied refrigerant. In this figure, 40 designates a thin 95 100

walled sheet metal cylinder which is closed at each end by a head 41 to form a container for refrigerant which is delivered thereto thru a conduit connection 42. The surface of the cylinder is helically corrugated by rolling or otherwise suitably forming a helical groove 43 which extends substantially from one end of the cylinder to the other. Inside of the corrugated cylinder is placed a second cylinder 45 which is open at one end 46 and is closed at the other end by a plate 47. The space between the plate 47 and its adjacent head 41 forms an inlet chamber 48 for the gaseous refrigerant and the space within the cylinder 45 forms a reservoir 49 for liquid refrigerant. The cylinder 45 fits against the bottoms of the helical corrugations and thus forms with the corrugated cylinder a helical passage 50 which leads from the inlet chamber to the reservoir 49 and directs the incoming gaseous refrigerant in a lengthy tortuous path about the condenser before it can reach the reservoir. Liquid refrigerant is withdrawn from the reservoir 49 by means of a pipe 52 leading to a connector 54 for the conduit 28 from a point near the bottom of a reservoir.

A cylindrical shell 55 is placed around the corrugated cylinder and its ends are joined to the latter, for example, by being spun over and sealed by means of soldered joints 56. The outer cylinder forms with the corrugated cylinder a helical passage 58 which is inter-threaded with and thus in intimate thermal relation with the helical passage 50. The outer shell 55 is provided with a water inlet connection 60 and a water outlet connection 61 both of which communicate with the helical passage 58.

40 The connector 54 is spun over the shell 40 and soldered thereto as indicated at 40a. The outer shell 55 is provided with an opening to permit passage of the connection 54 and the edges of this opening are sealed to the shell 40 by a soldered joint 40b. The shell 55 is also spun over the end plates 41 and is sealed to them by the soldered joints 56. It will thus be apparent that there is no joint which, if it should leak, will permit water to flow into the refrigerant within the system. All of the joints of the water passage are on the outside of the refrigerant container and therefore any water leaking thru faulty joints will merely flow out of the system. If a joint in the refrigerant container should leak the refrigerant may escape but since none of these joints lead into the water container no water can be drawn into the refrigerating system.

45 It is frequently desirable to be able to inspect the water passages of the condensers to detect lime or scale, for example, where the condensers are cooled by hard water or by sea water. In such instances I prefer to circulate the refrigerant outside of the water

and to construct the inner shell 45 so that it may be readily withdrawn to reveal the entire surface of the water passages. An arrangement for accomplishing this is shown in Figs. 4 and 5 wherein 40' is the helically corrugated shell, 55' is the outer shell having conduit connections 60' and 61' defining the outer helical passage 43', and 45' is the inner shell defining the inner helical passage 50'. All of the parts above enumerated are similar to the similarly numbered elements in Figs. 2 and 3. The ends of the shell 40' are spun over flanges 65 on collars 66 and are sealed to the collars by soldered connections 67. The ends of the shell are closed by plates 68 which are bolted to the collars 66 by bolts 70 the joints being made fluid-tight by means of gaskets 69. The above described apparatus forms a container to which water is supplied by a connection 72 and from which the water is withdrawn by the connection 73. Refrigerant entering the inlet connection 60' flows thru the tortuous passage 58' and is cooled and liquefied by the water within the container. In order to set up a flow of cooling water which is in effective thermal relation with, and counter to the flow of refrigerant, I place within the container a removable shell 45' which may be open at one end and closed at the other end by a plate 47' to form an inlet chamber 48' and the interior helical groove 50'. The open end of the shell 45' abuts the one head 68, the shell being held in position by a member 74 abutting the other head. Holes 76 near the open end of shell 45' permit water to flow from the helical passage to the discharge tube 73. The member 74 serves as a handle for withdrawing the shell 45' from the condenser when one head 68 has been removed. Withdrawal of the shell thus exposes the entire surface of the water passages to view and makes them accessible for cleaning.

50 The refrigerating element 22 is a water cooler in which a helically corrugated shell 80 similar to those previously described is closed at its ends by being spun over and soldered to end plates 82 and 83. A shell 84 is disposed outside of in contact with the shell 80 so as to form a helical passage 85 for circulating water. The shell 84 is provided with inlet and outlet connections 86 to conduct the water to and from the passage. The corrugated shell 80 forms a reservoir for liquid refrigerant which is supplied thereto by a branch of the liquid conduit 28 and is maintained at a substantially constant level therein by means of a valve 87 controlling the liquid inlet and actuated by the float 88. An outlet connection 89 is provided for withdrawing refrigerant evaporated in the shell. Preferably both the inlet and outlet connections are provided with shut-off valves 90. These valves as well as the float control mechanism are all mounted on a plate 92 which is

removably attached to the end plate 83 by bolts 94.

It will be observed that the water cooler shown minimizes the danger of water getting into the refrigerant conduits. The temperature control valve hereinafter referred to is intended to keep the water cooler always at a temperature above 32° F. and thus prevent freezing of the water even in the event that 10 no water is withdrawn from the cooler for a considerable period of time. However, in the event of accidental freezing of the water, the arrangement is such that any resulting breakage will not establish a leak between 15 the water passages and the refrigerant passages. If the joints at the ends of the container should break the water will merely escape but will not get into the container. Or, if the water should freeze at some point 20 intermediate the ends of the outer shell will burst before the inner shell for the reason that the compressive strength of the corrugated shell is greater than the tensile strength of the outer shell. The water cooler 25 is enclosed in any suitable insulating cabinet 95 which is provided with a spigot 96, connected to the water outlet passage 86 for withdrawing cooled water. The cooler is supplied with water by being connected to any 30 suitable supply conduit 97.

The refrigerating element 23 is formed of a helically corrugated shell 100 to which is secured, for example, by soldering, a cylinder 101 forming a helical passage 102. The shell 100 forms an enclosure for one or more ice-making containers 103 which are supported therein on thermally conducting shelves 104 which may be soldered to the sides of the container 100. Preferably the rear end of the 40 container is closed by the back plate 105, the front being left open to afford access to the ice-making containers. The shell 101 is provided with a refrigerant inlet connection 106 and a refrigerant outlet connection 107 to 45 which may be connected respectively a control valve 108 and vapor exhaust conduct 109. The control valve admits refrigerant from the liquid refrigerant under pressure from the liquid refrigerant reservoir in 50 response to the pressure existing in the passage 102, and thus tends to maintain a constant pressure therein. The particular construction of the control valve forms no part of the present invention, and any device which admits liquid refrigerant so as to maintain a substantially constant pressure within the cooling element will suffice. For example, the valve may be constructed as shown in the application of Harry B. Hull, Serial No. 55 733,884, filed August 25, 1924. Preferably the refrigerating element, including the container 101 and the control valve 108 is disposed in a refrigerating compartment 110 of a cabinet 111 and is supported therein by means of hangers 112 attached to straps 113 which

are secured to the top of the cabinet by any suitable means. The chilling effect of the cooling element on the air in the cabinet sets up circulation thru the openings 114 and 115 as is well known in the art.

The switch 30 which controls the operation of the system may be actuated by a bar 116 which is pivoted at 117 and is biased to open the switch by a spring 118. The switch may be closed by a thermostat such as a metal bellows 119 connected with a bulb 120 charged with a volatile liquid and thermally associated with the refrigerating element 22 or by a similar thermostat including a bellows 121 connected with a bulb 122 thermally associated with the cooling element 23. When there is a refrigerating demand upon either refrigerating element, its corresponding bellows will close the switch to operate the compressor.

Since the refrigerating element 22 is intended for cooling circulating water for drinking purposes and therefore operates at a temperature substantially above 32° F., and since cooling element 23 is intended to freeze ice and must therefore operate at a temperature substantially below 32° F., if the refrigerating demand of the water cooler 22 should be satisfied while there is still a demand on the refrigerating element 23, the compressor would continue to operate and would withdraw refrigerant from both the units. This would result in freezing the water. To prevent freezing, I place in the suction line leading from the water cooler an automatic valve 123 which closes the suction line in response to satisfaction of the refrigerating demand, and prevents further refrigeration. The particular construction of this valve forms no part of the present invention, and it may, for example, be a valve which is held open by high pressure in the suction line corresponding to a high temperature of the refrigerating element and which automatically closes in response to a low pressure in the suction line corresponding to the desired low temperature in the refrigerating element, as is more fully disclosed in the patent to Eddy, No. 1,185,596, filed May 30, 1916.

When the form of condenser shown in Figs. 2 and 3 is used in the system, the receiver 29 may be dispensed with and the condenser connected directly with the liquid supply line 28 since this form of condenser in addition to condensing refrigerant also provides efficient storage space for the refrigerant in the system.

While the form of embodiment of the present invention as herein disclosed, constitutes a preferred form, it is to be understood that other forms might be adopted, all coming within the scope of the claims which follow.

What is claimed is as follows:

1. A cooling element for refrigerating systems comprising a liquid reservoir having a

- helically corrugated wall of uniform thickness, a tubular member cooperating with the wall to form a helical passage for circulating fluid, and a second tubular member surrounding the corrugated shell and providing a second fluid passage.
2. A cooling element for refrigerating systems comprising in combination a reservoir for liquid refrigerant having a helically corrugated wall, a tubular member cooperating with the outside of the wall to form a helical fluid passage, and a tubular member cooperating with the inside of the corrugated wall to form a second helical fluid passage.
- 16 3. A cooling element for refrigerating systems comprising in combination a tubular container for liquid refrigerant, a helically corrugated tubular member surrounding the container and cooperating therewith to form a helical passage for gaseous refrigerant and means for condensing the gaseous refrigerant including a tubular member surrounding the corrugated member and forming therewith a helical passage for circulating cooling medium.
- 20 4. A cooling element for refrigerating systems comprising in combination, a helically corrugated tubular member, a tubular member surrounding the corrugated member to form a helical passage for refrigerant, a tubular member inside the corrugated member and cooperating therewith to form a helical passage for the cooling medium, said inside tubular member being removable to permit inspection of the cooling medium passages.
- 25 5. A cooling element for refrigerating systems comprising in combination a helically corrugated tubular member, means removably secured to the ends of the tubular member to form a liquid container, a removable tubular member within the container cooperating with the corrugated member to direct liquid flowing into the container in a helical path, and a tubular member surrounding the container and cooperating with the corrugated member to form a helical passage for refrigerant.
- 30 6. A cooling element for a refrigerating system comprising a liquid chamber having a helically corrugated wall of uniform thickness, a tubular member cooperating with the wall to form an integral fluid passage connecting with said liquid chamber, and a second tubular member spaced from said first mentioned tubular member and surrounding said helical wall and said first mentioned tubular member to provide a separate fluid chamber.
- 35 60 In testimony whereof I hereto affix my signature.

JESSE G. KING.
